UNITED STATES PATENT OFFICE.

HAROLD G. WEIDENTHAL, OF CLEVELAND, OHIO; LOUISE S. WEIDENTHAL ADMINISTRATRIX OF SAID HAROLD G. WEIDENTHAL, DECEASED.

FURNACE.

1,410,086.

Specification of Letters Patent. Patented Mar. 21, 1922.

Application filed July 29, 1920. Serial No. 399,706.

To all whom it may concern:

Be it known that I, HAROLD G. WEIDENTHAL, a citizen of the United States, residing at Cleveland, in the county of Cuyahoga and State of Ohio, have invented a certain new and useful Improvement in Furnaces, of which the following is a full, clear, and exact description, reference being had to the accompanying drawings.

10 This invention relates to metallurgical furnaces and especially to electric furnaces although not by any means limited thereto. The objects of the invention are the provision of a roof and lining so constructed as to possess greater mechanical strength and longer life than heretofore; the provision of a new and improved mode of securing in place a lining of a furnace; the provision of a furnace lining and roof which shall better withstand the high temperatures to which they are subjected; the provision of an improved brick or block for furnace linings; while further objects and advantages will appear as the description proceeds.

25

The temperatures employed in many metallurgical operations of the present day are higher than the melting point of the material of which the furnace itself is made, as a consequence of which the furnace lining is rapidly melted or eroded away until it reaches such a thickness that the heat loss from the exterior brings the interior surface down to a temperature that the furnace material will survive. This thickness varies with the heat conductivity of the different substances used for linings and also with the furnace construction which may affect the rate of heat loss from the exterior surfaces. With brick of the type ordinarily used for the roof of electric furnaces, equilibrium is generally attained when a thickness of approximately five inches has been attained, yet the bricks are generally made with an original thickness of about nine inches for the purpose of securing greater mechanical strength. The result is that half the thickness of the brick is melted or eroded away within the first few hours of operation, after which the furnace remains constant until the occurrence of a slight blow or jar which causes the collapse of the roof due to its deficiency of mechanical strength. Likewise the wall bricks are generally 15 to 18 inches thick when new but do not reach

equilibrium until burned back to about 9 inches.

According to my invention, I form each brick with an external cavity open to the outer air and extending inwardly into the brick sufficiently far so that its cooling effect is sufficient to prevent any serious destruction of the inner surface. In this way I secure sufficient lateral surface of each brick to afford the necessary mechanical strength while also securing sufficient radiation to maintain the inner face of the brick at a sufficiently low temperature to prevent serious disintegration. I also utilize this construction as part of an expedient to secure 70 the lining bricks in place upon the furnace wall by forming such wall with metal studs which enter the cavities in the bricks and hold them in place. This feature is peculiarly important across the tops of doors and working openings where it is difficult to support the lining bricks, and at the upper rearward wall of tilting furnaces, and in places where bricks are frequently renewed. It is a further feature of my invention to introduce into the cavity of the brick a material of higher conductivity than the brick substance, thereby still further tending to maintain the integrity of the lining. As a practical matter it is far more 80 economical to suffer a slightly increased heat loss and thereby maintain the furnace in condition a longer period of time than to save a few per cent in current used at the cost of frequent repairs and long shutdowns. 90

In the drawings accompanying and forming a part of this application, I have shown the preferred embodiment of my invention although it will be understood that the illustrations herein are merely suggestive of types and not exhaustive of structure. In these drawings, Fig. 1 represents a top plan view of one design of a top for electric furnaces; Fig. 2 is a vertical sectional view 100 through the top and side walls of the furnace; Fig. 3 is a sectional view of the furnace drawn to smaller scale and showing the same in tilted position; Fig. 4 is an enlarged sectional view through one of the 105 top bricks; and Fig. 5 is an enlarged sectional view through one of the wall bricks together with its support.

The top of such a furnace ordinarily comprises a circular metal hoop 1 having built 110

immediately within it a ring 2 of fire brick or other refractory material which in turn supports the arched roof formed of bricks 3-3 of various shapes and sizes. Different manufacturers employ different designs, and the particular design shown is not important to my invention. However, I form each brick which is subjected to the furnace heat with one or more outwardly opening cavities 5 of such depth as to cool the interior face of the brick to the necessary degree and also to afford a sufficiently wide lateral face to secure the desired mechanical strength. The side wall of the furnace is generally made of a metal shell 10 lined interiorly with bricks 11, the lower portions being lined in turn with a refractory hearth material 12, generally molded in place. The sides of the shell are formed with a pouring opening 13 and one or more working openings 14, while the top is closed by means of the cover previously described which rests more or less tightly thereon. According to my invention, I form each of the wall bricks 15 above the hearth with an outwardly opening cavity 15, and I preferably provide the shell with inwardly projecting metal studs 16 upon which these bricks are lodged. These studs are also preferably hollow, for 20 the double purpose of permitting the access of air to the brick interior and also of enabling the insertion of a rod with which to knock the brick from its seat if and when it is desired to replace the same. These 25 studs, whether hollow or solid, act by reason of the increased conductivity to cool the brick material and hence to reduce the temperature of its inner face, and also permit the movement of air to cool the bricks. They are preferably held in place by spinning or riveting the metal thereof into contact with the metal shell, although the same 30 can be bolted in place if desired. The studs are generally located in a slanting position 35 with their inner ends uppermost, and the individual bricks formed with their upper and lower faces parallel to the cavity and oblique to their end faces, thus causing a kind of interlocking which greatly impedes 40 their accidental dislocation. This construction not only renders the furnace lining longer lived but facilitates the replacement of individual bricks since the various units 45 are not so dependent upon each other for their support as heretofore. This is a particularly important feature at the top of the furnace and near openings because of the accidental damage to the lining due to mechanical shocks and to the erosive action of 50 55 60

It will be understood that I do not restrict myself to a construction in which the furnace has a complete external shell, since the same can be made as a skeleton or even omitted; and likewise many other modifications

can be made within the scope of my invention; wherefore I do not limit myself in any manner except as specifically recited in the claims hereto annexed.

Having thus described my invention, what I claim is:—

1. A brick or lining unit for metallurgical furnaces made of refractory material and having an outwardly opening cavity of uniform bore throughout and extending sufficiently near the inner face thereof to assist in cooling the same. 75

2. A brick or lining unit for metallurgical furnaces consisting of a hollow flat sided block of refractory material having an opening only in that face which is turned outwardly, the bore of said cavity being uniform from end to end. 80

3. A brick or lining unit for metallurgical furnaces made of refractory material and having an outwardly opening cavity extending to a point sufficiently near the inner face thereof to assist in cooling the same, and a hollow heat conducting body located in said cavity, said body being open at both ends. 85

4. In a device of the character described, a lining built up of blocks of refractory material and being the thickness of a single block, certain blocks having cavities opening through their outer faces and extending sufficiently near the inner faces of the same to assist in cooling them, the cavities being of uniform bore throughout. 90 95

5. In a furnace, a metal shell, a lining therein consisting of blocks of refractory material, certain of which have cavities in their outer faces, and metal studs attached to said shell and projecting into said cavities, so as to hold the blocks in place and also to conduct heat away from their inner faces. 100 105

6. In a furnace, a metal shell, a lining therein consisting of blocks of refractory material, formed with cavities in their outer faces, and heat conducting bodies in said cavities, said bodies making thermal contact with said shell. 110

7. In a furnace, a metal shell, a lining therein consisting of blocks of refractory material, certain of said blocks having in their outer faces a cavity which extends sufficiently near the inner face to assist in cooling the same, in combination with hollow metal studs carried by said shell and projecting into said cavities. 115

8. In a furnace, in combination, a metal shell having a plurality of inwardly projecting oblique metal studs, and lining blocks of refractory material having cavities loosely receiving said studs. 120

9. In a furnace, in combination, a metal shell having a plurality of inwardly projecting hollow oblique metal studs, and lining blocks of refractory material having cavities loosely receiving said studs. 125

10. In a furnace, in combination, a metal

shell having a plurality of inwardly projecting oblique metal studs, and lining blocks of refractory material having cavities loosely receiving said studs, the sides of said blocks which contact with other blocks being parallel to said studs and the sides which do not contact with other blocks being perpendicular to the studs.

11. In a furnace, in combination, a metal shell having a plurality of inwardly projecting oblique metal studs, and lining blocks of refractory material having cavities loosely receiving said studs, the sides of said blocks being parallel to said studs and the inner faces of said blocks being parallel to the shell at that point.

12. In a furnace, in combination, a metal shell having a plurality of inwardly projecting, hollow, oblique, metal studs, and lining blocks having cavities loosely receiving said studs, the sides of said blocks which contact with the other blocks being parallel

to said studs and the inner face of said blocks being parallel to the metal shell at that point.

13. A lining block for furnaces made of refractory material and having the shape of an oblique parallelepipedon, there being a cylindrical cavity opening through one face of the same.

14. A refractory lining block for furnaces made in the shape of an oblique parallelepipedon and having a cylindrical cavity opening through a single face thereof, the axis of said cavity being parallel to the side faces of the block and oblique to that face through which it opens.

15. A roof for furnaces made of blocks of refractory material whose outer faces are formed with cavities which extend inwardly adjacent their inner surfaces.

In testimony whereof, I hereunto affix my signature.

HAROLD G. WEIDENTHAL.
